BULB COATING PROCESS

August E. Binder, Jr., Mentor-on-the-Lake, Ohio,
assignor to General Electric Company, a corpora-
tion of New York

Application April 29, 1953, Serial No. 351,985

3 Claims. (Cl. 117—10)

1

My invention relates in general to a method of interiorly coating vitreous envelopes, such as lamp bulbs and the like, having a single opening thereto, and especially to a method of applying a luminescent material to the inner surface of a selected portion of such envelopes.

Certain types of fluorescent lamps in general use at present employ a glass enclosure envelope or bulb having a bulbous portion provided with tubular extensions at its opposite ends one of which is closed off and the other of which is open at its outer end to form the neck portion of the bulb, the inner surface of the bulbous portion of the bulb being provided with a coating of fluorescent material while the tubular extensions are left clear. For satisfactory appearance it is desirable that the limiting or cut-off edges of such fluorescent phosphor coatings be as straight as possible around the bulb and not of wavy or otherwise irregular character. However, because the outer rim end of the neck portion of such bulbs normally is of irregular form with sharp and jagged edges such as preclude the use of a conventional pressure upflush method of applying the coating to the bulb wall by reason of the difficulty of forming an airtight seal with such irregular edges, the formation of phosphor coatings with more or less straight cut-off edges heretofore has been a difficult and inconvenient operation to perform, the method previously in use having been to first coat the entire inner surface of the bulb with the phosphor material and to then remove the coating from the tubular extensions of the bulb by a hand operation such as by brushing or wiping.

It is an object of my invention, therefore, to provide an improved method of applying a coating to a selected area of the inner surface of a lamp envelope or other hollow article having a single opening thereto, which method is easy and convenient to perform and requires a minimum expenditure of time.

Another object of my invention is to provide an improved method of applying an internal fluorescent coating to the intermediate portion only of a tubular lamp envelope having an opening at one end only, whereby the cut-off edges of the coating are formed substantially straight.

According to one aspect of the invention, a coating of fluorescent material is first applied to the inner wall of the lamp envelope extending inwardly from the open neck end thereof to the desired level for the innermost cut-off edge of the coating, by suction of a suspension of the fluorescent coating material upwardly into the

2

envelope to the said level, immediately followed by washing of the fluorescent coating off the neck end portion of the envelope up to the desired lower cut-off level for the coating while simultaneously directing air through the envelope to rapidly dry the remaining coating on the bulb wall before it has an opportunity to drain therefrom such as would result in the formation of undesirably thin and non-uniform coatings.

10 Further objects and advantages of my invention will appear from the following description of a species thereof and from the accompanying drawing in which:

Fig. 1 is a vertical section through a lamp envelope and associated apparatus employed to perform the first or coating application step of the method comprising my invention, and

15 Fig. 2 is a vertical section through the envelope and associated apparatus employed to perform the second step of the method comprising my invention wherein the portion of the coating on the lower or neck section of the envelope is removed and the remainder of the coating on the envelope is dried in place on the envelope wall.

20 The invention is herein described and illustrated with reference to the formation of an internal coating of fluorescent material on a selected intermediate portion of the length of a tubular glass envelope or bulb 1 which is closed at one end but open at the other end, the particular bulb illustrated having an enlarged oval-shaped or bulbous center portion 2 provided with cylindrical extensions 3 and 4 at its opposite ends, the extension 3 being open at its outer end and constituting the neck portion of the lamp envelope and the other extension 4 being closed off at its outer end by an end closure wall 5. It should be understood, however, that the invention can be utilized to apply any coating material of the type which can be flushed onto the surface to be coated, and that it is applicable to the coating of envelopes of shapes other than tubular which have a single entrance opening thereto.

25 30 35 40 45

To provide an internal fluorescent coating on an intermediate portion of the length of the bulb 1, for instance on the bulbous portion 2 only, by the method according to the invention, the portion of the inner bulb surface extending from the open end 6 of the neck portion 3 inwardly to the innermost cut-off line 7 desired for the final coating, is first flush-coated with a layer 8 (Fig. 2) of fluorescent material by suction of a suspension of a fluorescent material upwardly

50 55 into the bulb while the latter is positioned with

its open neck end down. For this purpose, the neck end 3 of the bulb is placed over a vertical suction tube 9 extending upwardly from the bottom wall 10 of a container 11 filled with the coating suspension 12 to be applied to the bulb wall, the bath of coating suspension 12 being exposed to atmospheric pressure. The phosphor coating suspension 12 may be any of the types customarily employed in fluorescent lamp manufacture for applying coatings of fluorescent material to the walls of the lamp envelopes, such phosphor suspensions usually comprising a fluorescent phosphor powder suspended in a suitable binder such as nitrocellulose dissolved in a suitable solvent or thinner such as butyl acetate or amyl acetate, with or without naphtha, for instance. The vertical suction tube 9 is open at its upper end and is joined at its lower end to the bottom wall 10 of the container 11 in a liquid-tight manner. The bulb 1 is moved down over the vertical suction tube 9 until the upper end 13 of the latter is located above the innermost or upper cut-off level 7 for the coating and until the lower neck end 3 of the bulb is completely submerged in the coating suspension bath 12 a sufficient distance to remain submerged when part of the coating suspension 12 in the container 11 is drawn up into the bulb to the desired upper cut-off level 7 for the coating. The bulb may be conveniently supported in place by resting the end closure wall 5 of its top extension 4 on the upper end 13 of the suction tube 9, the said tube for such purpose being of sufficient height to locate the open neck end 3 of the bulb up off the bottom wall 10 of the container 11 so as to permit free flow of the coating suspension 12 from the container into the bulb neck 3. The suction tube 9 communicates at its lower end with a conduit or pipe 14 which is adapted to be connected, by a valve 15 in the said conduit, either to a source of vacuum, or alternatively to the atmosphere so as to vent the suction tube 9. The upper end or rim 13 of the suction tube 9 is suitably notched as indicated at 16 to provide passageways interconnecting the interior of the tube 9 with the interior space of the bulb.

With the bulb 1 rested in position on the top 13 of the suction tube 9 and its lower neck end 3 immersed in the coating suspension 12 in the container 11, as shown in Fig. 1, the valve 15 is set so as to connect the suction tube 9 to the source of vacuum. The resulting suction created in the tube 9 and bulb 1 then draws the coating suspension 12 in the container 11 up into the bulb. When the rising column of coating suspension in the bulb 1 reaches the desired upper cut-off level 7, which for the particular type of lamp bulb illustrated is located approximately at the junction between the enlarged bulbous portion 2 and the upper cylindrical extension 4 of the bulb, the vacuum is shut off by means of the valve 15 and the suction tube 9 then connected instead to the atmosphere by the valve so as to vent the tube 9 and the interior of the bulb, as a result of which the column of coating suspension in the bulb recedes approximately to its original starting level equalized with that of the coating suspension 12 outside the bulb. It will be obvious that by the use of the above-described particular up-flush coating operation the rising column of coating suspension in the bulb will produce a perfectly smooth and straight upper cut-off edge around the bulb defining a plane normal to the bulb axis, if care is taken to see that the bulb is supported on the suction tube 9.

in true vertical position during the coating application operation.

Immediately after the coating 8 has been thus flushed onto the interior wall of the bulb 1, the bulb is carefully lifted off the suction tube 9 so as not to mar the coating deposited on the bulb wall, and the said coating 8 then rapidly dried and set in place by the passage of a low velocity air current through the bulb to thereby minimize the drainage of the wet coating downwardly along the bulb wall such as would cause the coating to thin out with resulting formation of an undesirably thin and non-uniform coating. In addition, where the neck portion 3 of the bulb is to be also left clear or free of coating, the portion of the phosphor coating on the neck portion 3 of the bulb 1 is suitably removed.

In accordance with the invention, this phosphor coating removal operation is preferably performed simultaneously with the air drying of the coating on the bulbous portion 2 of the bulb. For such purpose the phosphor coated neck end portion 3 of the bulb 1 is immersed up to the desired lower cut-off level 17 in a bath 18 (Fig. 2) of thinner material such as customarily employed as a solvent for the nitrocellulose or other binder used in phosphor coatings, examples of which thinner material have been previously mentioned. The thinner bath 18 is preferably contained in a toroidal-shaped container or cup 19 into the annular chamber of which the neck end 3 of the bulb is inserted to the required depth to effect immersion of the phosphor coating on the bulb neck up to the desired lower cut-off level 17 which, for the particular type of lamp illustrated, is located approximately at the junction between the enlarged bulbous portion 2 and the cylindrical neck portion 3 of the bulb. The bulb 1 may be supported in proper position relative to the thinner bath 18 to effect the desired extent of immersion of the bulb neck therein by resting the bulbous portion 2 of the bulb on the upper annular rim or end 20 of the container 19. The thinner bath 18 acts to maintain in suspension and thus wash the phosphor coating off the bulb neck up to the level thereof immersed in the thinner bath so that when the bulb neck is subsequently removed from the thinner bath the said portion of the bulb neck will be left substantially clear, and the phosphor coating 8 remaining on the bulb wall will be formed with a smooth and straight lower cut-off edge 17 around the bulb. To maintain the thinner bath 18 in the container 19 at the desired lower cut-off level 17 for the coating 8 and prevent it from rising above such level by reason of the tendency of the phosphor coating washed off the walls of successive bulbs to increase the volume of the thinner bath 18, the container 19 is provided with a suitable overflow outlet or spout 21.

During the interval while the neck end 3 of the bulb 1 is immersed in the thinner bath 18, low velocity air, which may be heated if desired, is discharged into the interior space of the bulb above the level of the thinner therein, preferably into the top region of the bulb within the cylindrical top extension 4 thereof, from a vertical air inlet tube 22 which is of smaller diameter than and extends up through the central passageway 23 of the toroidal container 19 to a point adjacent the top 5 of the bulb. The lower end of the air inlet tube 22 is connected to a supply of low pressure air. The low velocity air passing out of the upper end 24 of the air inlet tube 22 then flows downwardly through the interior space of

the bulb, as indicated by the arrows in Fig. 2, where it comes in contact with and dries the phosphor coating 8 on the inner surface of the bulb wall. The air stream passes out of the bulb through the annular space between the air inlet tube 22 and the wall 25 of the central passageway 23 in the toroidal container 19.

When the phosphor coating 8 on the bulb wall has been sufficiently dried and set in place thereon, the bulb is withdrawn from the thinner bath 18 in the container 19 to thereby complete the coating operation.

What I claim as new and desire to secure by Letters Patent of the United States is:

1. The method of applying a coating of powdered material to the inner surface of a selected portion of the length of an envelope having an open-ended neck portion providing the only opening thereto, which method comprises inserting the envelope neck end down into a bath comprising a suspension of the coating material exposed to atmospheric pressure to completely submerge the open end of the said envelope neck portion in the said suspension bath, withdrawing the air in said envelope from a region adjacent the top thereof to create a suction therein and draw the said coating suspension up into the envelope, venting the interior space of the envelope above the coating suspension therein to the atmosphere when the column of coating suspension attains the desired predetermined upper cut-off level for the coating, to cause the column of coating suspension in the envelope to recede therefrom, and immediately immersing the neck end portion of the envelope up to the desired predetermined lower cut-off level for the coating in a thinner for the said coating suspension while simultaneously passing a low velocity air stream through the interior space of the envelope above the thinner therein to dry and set in place the coating deposited on the inner wall of the envelope.

2. The method as set forth in claim 1 wherein the said air stream is directed downwardly

through the envelope from the top region thereof.

3. The method of applying a coating of powdered material to the inner surface of a selected portion of the length of an envelope having an open-ended neck portion providing the only opening into the envelope, which method comprises positioning the envelope neck end down over a vertically extending tube with the upper end of the said tube located above the desired upper cut-off line for the coating on the envelope and the open neck end of the envelope completely submerged in a bath comprising a suspension of the coating material, connecting the lower end of the said tube to a source of vacuum to create a suction in the tube and envelope and draw the said coating suspension up into the envelope, disconnecting the said tube from the vacuum source and venting it to the atmosphere when the rising column of coating suspension attains the said upper cut-off line for the coating, to cause the column of coating suspension in the envelope to recede therefrom, and then immediately placing the neck end of the envelope over a vertical air outlet tube upstanding from the bottom of a container filled with a liquid thinner for the said coating suspension and immersing the said neck end of the envelope in the said thinner up to the desired lower cut-off line for the coating on the envelope while simultaneously introducing a low velocity stream of air into the top region of the envelope, through a vertical air inlet tube extending through the said air outlet tube, to dry and set in place the coating deposited on the inner wall of the envelope.
